UNITED STATES PATENT OFFICE.

GEORGES EZBELENT AND ROGER EZBELENT, OF PARIS, FRANCE, ASSIGNEES TO THE COMPANY: EZBELENT FILS, OF PARIS, FRANCE.

PLAITING MACHINE.

Application filed March 9, 1928, Serial No. 260,498, and in France December 30, 1927.

The present invention relates to plaiting machines in which an upper and a lower knife are pivotally mounted on a common axle and are reciprocated towards and away from the drums in a forward and a backward stroke.

In the known machines of this type, the lever causing the pivotation of the knives is controlled by a cam provided with removable bosses, in such manner that according as the said lever makes contact with a raised or a concave cam portion, the knives will assume the upper or lower position, or inversely.

According to the present invention, the pivotation of the said knives is effected by means of a member positively driven which causes said knives to be pivoted towards one of the drums during one of said strokes against the action of yielding means urging constantly said knives towards the other drum, means being adapted to relieve the knives from the action of the member positively driven.

The said relieving means may be controlled by a cam provided with fixed or removable bosses, known per se.

Further advantages and features of the invention will be specified in the following description with reference to the appended drawings which show by way of example an embodiment of the invention.

Fig. 1 is an elevational view of the machine.

Fig. 2 is a plan view showing the device for the control of the movable stop by means of cams provided with bosses.

Fig. 3 shows the sector for holding the said device.

The upper and lower knives of the machine, 1-2, are supported by the cheeks 3 and are given a reciprocating motion by these latter, whereby they are moved from or towards the drums 4 and 5. The cheeks 3 together with the knives 1 and 2 are pivotally mounted on the axle 6, so that the said knives may slide upon the upper forming plate 7 or on the lower forming plate 8. This movement of pivotat-

in the known manner by two arms 13 pivoted to the cheeks 3 and connected together in an elastic manner by the spring 14. The pivoted plate 10 is actuated by a lever 15 pivoted upon an axle 16 and connected with the plate 10 by means of the sliding member 17 whose position may be adjusted in the slot 18 of the plate 10. The lever 15 is controlled by the spring 19 in such manner that the roller 20 mounted on this lever will make contact with the rotatable cam 21 having a continuous outline. The said cam has two curved parts, one of which *a-b-c* which is relatively nearer the centre of the cam, whilst the other part *a-d-c* is farther removed, the construction being such that when the roller 20 makes contact with the respective curved parts of the cam, the knives 1 and 2 will be raised or lowered. The speed of rotation of the cam 21 is regulated in such manner that the outline *a-b-c* will correspond to the forward motion of the knives towards the drums 4-5, and that the outline *a-d-c* will correspond to the back motion of the said knives with reference to the drums.

In this manner, if the machine would comprise only the aforesaid parts, the knives, in their forward motion, would slide along the upper formation plate 7, and in their back motion, they would slide along the lower formation plate 8, and herein the machine would make only overlapping plaits.

If the lever 15 is held constantly in the position corresponding to the contact between the roller 20 and the curved outline *a-d-c* which is farthest from the centre of the cam, the knives 1 and 2 will constantly follow the lower formation plate 8, during the forward as well as the back motion of the knives. We may thus constantly obtain underlapping plaits by maintaining the lever 5 in the said position by the use of a movable tappet. In this example, such a movable tappet consists of a hook 22 pivoted on the axle 23 and engaging a catch 24 mounted on the lever 15. A spring 25 urges the hook 22 into contact with the catch 24. In this manner, when the hook 22 engages the catch 24, the machine will constantly produce underlapping plaits, and when the said hook is released from the said

catch, the machine will constantly produce overlapping plaits. To obtain overlapping or underlapping plaits as desired, the hook 22 is movably mounted on the axle 23 so that it 5 may make contact with the catch 24 or may move out of contact therewith.

However, the hook may be placed in or out of contact with the catch 24 by means of cams provided with fixed or movable bosses, where- 10 by we may obtain a succession of plaits in a stated order so as to produce various patterns on the fabric. For this purpose, the sleeve 26 carrying a contact roller 27 is slideable on the axle 23. The said roller may be made 15 to coincide with one of the cams 28, 29, 30, 31 mounted on the axle 32 which is parallel with the axle 23, or it may be placed in the space between any two of the cams. The said cams may be provided with removable bosses, and 20 they are preferably constructed according to the U. S. Patent No. 1,612,500. The said cams may also consist of discs with fixed bosses. In this manner, a disc may offer alternately a boss and a concave part in order to obtain box 25 plaits. When the roller 27 makes contact with a concave part, the hook 22 is engaged with the catch 24, but when the said roller en- 30 gages a raised part, said hook will be released from the catch. The cams such as 28, 29, 30, 31 may be used in any suitable number, and in this manner the plaits will succeed one another in any desired order. For instance, if 35 box plaits are to be formed, the roller 27 is made to coincide with a cam having alter- nately a boss and a concavity. When the 40 roller 27 is brought into the space between any two cams, the hook 22 under the control of the spring 26 will engage the catch 24, so that the machine constantly produces underlapping 45 plaits. The roller 27 may be operated by a lever 33 which is pivoted to the sleeve 26 and is pivotally mounted on a ball joint 34 (or the like) by which the lever may turn upon dif- 50 ferent axes. The said lever may be held in the respective positions of the roller 27, by means of a sector 35 having the notches 35', 36, 37, 38, 39 in which the lever can be fastened. The notches 36 to 39 correspond to the respective 55 cams 28, 29, 30, 31, whilst the notch 35' corresponds to a lower position of the roller 27 in which the hook 22 engages the catch 24.

Between the notches, the sector comprises the raised parts 40, so that in passing from one notch to another, the lever is obliged to 60 pass over the raised parts and it accordingly rotates the sleeve 26, and the roller 27 is thus raised out of contact with the cams 28 to 31. With the roller 27 in the raised position, the lever 33 can be used to bring the said roller into any position without meeting with the 65 cams.

The controlling lever 33 may in turn be automatically controlled by a cam of suitable outline.

65 The plaiting machine herein specified has

many advantages over the known plaiting machines, which may be stated as follows:

1. The oscillating motion of the knives is obtained by the control of a cam which has a continuous outline and is given a regular rotation, thus providing for the positive control of the knives, and we are thus enabled to optionally eliminate the elastic combination 13, 14. The bosses on the cam 21 may be as considerable as desired, and this affords the reduction of the lever gear which was necessary when the lever 15 was controlled directly by a cam with removable bosses. The position of the knives is controlled by the complete rotation of the cam 21, and not as in the machines employing a cam provided with bosses and having an intermittent rotary motion, by a rotation through a very small angle correspond- 70 ing to half the angular distance between two successive bosses, and we thus obviate the 75 shocks in the machine, so that it will operate in a very easy manner.

2. The cams provided with bosses 28 to 31, which control the movable tappet and have an intermittent motion, are moved only once 80 during a complete stroke of the knives, i. e. during the forward and backward motion 85 of the said knives.

3. It is no longer necessary to provide 90 empty spaces between two successive removable bosses, so that these bosses may be placed side by side, whereby we are enabled to reduce the diameter of the cam provided with bosses, or to increase the number of such 95 bosses by increasing the number of combina- 100 tions.

4. The said bosses may have a relatively 105 small size, for in the present machine, the bosses serve only to release the stop 22, whilst in the known machines the bosses must pro- 110 ject considerably from the surface, since they must provide for the whole amount of motion of the knives.

5. The machine need not be stopped in order 115 to change the combinations, since the roller 27 may be placed at will, and without obstacle, in coincidence with any desired cam.

6. Without modifying any of the combina- 120 tions formed on the cams provided with the removable bosses, we may produce overlapping or underlapping plaits respectively by placing the controlling lever 33 upon the projecting parts 40 or by lowering the said lever in the notch 35' so as to bring the hook 22 into engagement with the stop 24.

Obviously, our said apparatus is susceptible 125 of various modifications without departing from the spirit of the invention.

For example, the cam 21, instead of con- 130 stantly producing overlapping plaits, may constantly produce underlapping plaits, by inverting the respective positions of the point of pivot 11 and of the sliding member 17. In this event, the hook 22 will act upon the catch 24 to produce the overlapping plaits.

Having now described our invention, what we claim as new and desire to secure by Letters Patent is:

1. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, elastic means adapted to urge said frame with said knives towards one of said drums, controlling means adapted to pivot said frame with said knives towards the other drum against the action of said elastic means, and movable locking means adapted in their operative position to hold permanently said frame with said knives towards said other drum. 70
2. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, elastic means adapted to urge said frame with said knives towards one of said drums, controlling means adapted to pivot said frame with said knives towards the other drum against the action of said elastic means during one of said strokes of said frame, and movable locking means adapted in their operative position to hold permanently said frame with said knives towards said other drum. 80
3. In a plaiting machine the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a movable member adapted to move said lever in the other of said directions during one of said strokes of said frame, a movable stop piece adapted in its operative position to hold permanently said lever in an extreme position corresponding to said other direction. 90
4. In a plaiting machine the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a rotatable cam having a continuous working surface on which said lever is adapted to bear, said working surface having at least one boss corresponding to one of said strokes of the frame, whereby said lever is moved in the other of said directions, and a movable stop piece adapted in its operative position to hold permanently said lever in the extreme position corresponding to said boss. 100
5. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, elastic means adapted to urge said frame with said knives towards one of said drums, controlling means adapted to pivot said frame with said knives towards the other drum against the action of said elastic means during one of said strokes of said frame, moveable locking means adapted in their operative position to hold permanently said frame with said knives towards said other drum and adjustable means for bringing in any predetermined sequence said locking means into their operative and their inoperative position. 110
6. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum, when moved in the opposite direction, elastic means urging said lever in one of said directions, a movable member adapted to move said lever in the other of said directions during one of said strokes of said frame, a movable stop piece adapted in its operative position to hold permanently said lever in an extreme position corresponding to said other direction and a rotatable cam adapted to bring said stop piece in its operative and in its inoperative position. 120
7. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a rotatable cam having a continuous working surface on which said lever is adapted to bear, said working surface having at least one boss corresponding to one of said strokes of the frame, whereby said lever is moved in the other of said directions, and a movable stop piece adapted in its operative position to hold permanently said lever in the extreme position corresponding to said boss. 130

ward and a backward stroke, a movable lever adapted to raise said frame with said knives towards the upper drum when moved in one direction and to lower said frame with said knives towards the lower drum when moved in the opposite direction, elastic means urging said lever in one of said directions, a movable member adapted to move said lever in the other of said directions, during one of said strokes of said frame, a movable stop piece adapted in its operative position to hold permanently said lever in an extreme position corresponding to said other direction and a rotatable cam with removable bosses adapted to bring said stop piece in its operative and in its inoperative position.

8. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a movable member adapted to move said lever in the other of said directions during one of said strokes of said frame, a movable stop piece adapted in its operative position to hold permanently said lever in an extreme position corresponding to said other direction, a number of rotatable cams and means operatively connecting with said stop piece and adapted to be engaged by any one of said rotatable cams.

9. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a movable member adapted to move said lever in the other of said directions during one of said strokes of said frame, a pivoting axle, a movable stop piece secured on said axle and adapted in its operative position to hold permanently said lever in an extreme position corresponding to said other direction, rotatable cams mounted in parallel relation with said pivoting axle, a sleeve on said axle adapted to be rotated with said axle and to be moved along said axle, and a con-

tact member carried by said sleeve and adapted to be moved with said sleeve into and out of the path of said cams.

10. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a movable member adapted to move said lever in the other of said directions during one of said strokes of said frame, a pivoting axle, a movable stop piece secured on said axle and adapted in its operative position to hold permanently said lever in an extreme position corresponding to said other direction, rotatable cams mounted in parallel relation with said pivoting axle, a sleeve on said axle adapted to be rotated with said axle and to be moved along said axle, a contact member carried by said sleeve and adapted to be moved with said sleeve into and out of the path of said cams, and an operating member operatively connected with said sleeve and adapted to be moved in one direction whereby said sleeve is caused to slide on said axle and in another perpendicular direction whereby said sleeve is caused to rotate and to bring said contact member out of the path of said cams.

11. In a plaiting machine, the combination of two plaiting upper and lower drums, an upper and a lower knife, a pivoted frame supporting said knives and adapted to be pivoted with said knives towards the upper and towards the lower drum and to be reciprocated towards and away from the drums in a forward and a backward stroke, a movable lever adapted to raise said frame with said knives towards the upper drum when moved in one direction and to lower said frame with said knives towards the lower drum when moved in the opposite direction, elastic means urging said lever in one of said directions, a movable member adapted to move said lever in the other of said directions during one of said strokes of said frame, a pivoting axle, a movable stop piece secured on said axle and adapted in its operative position to hold permanently said lever in an extreme position corresponding to said other direction, rotatable cams mounted in parallel relation with said pivoting axle, a sleeve on said axle adapted to be rotated with said axle and to be moved along said axle, a contact member carried by said sleeve and adapted to be moved with said sleeve into

and out of the path of said cams, an operating member operatively connected with said sleeve and adapted to be moved in one direction whereby said sleeve is caused to slide on said axle and in another perpendicular direction whereby said sleeve is caused to rotate and to bring said contact member out

of the path of said cams and a grooved sector adapted to hold said operating member in its different positions.
